UNITED STATES PATENT OFFICE

JOHN S. STRINGFELLOW, OF LINDSAY, VIRGINIA

KNIFE CONSTRUCTION

Application filed October 26, 1928. Serial No. 315,251.

The present invention has reference to a novel form of container designed primarily for containing razor blades of a well known type, the container being so constructed that it may be readily and easily converted into a knife by utilizing one of the razor blades from the container, as the knife blade.

An important object of the invention is to provide a container of this character including a removable blade carrying member in one end thereof, the blade being held in the blade carrying member by frictional contact therewith so that when pressure is directed to the free end of the blade, the blade will be forced through the blade carrying member and into the container.

A still further object of the invention is the provision of a container of the character that may be manufactured at such a low cost that the container may be distributed to users, gratis, thereby providing an exceptionally effective advertising medium.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a longitudinal sectional view through a container showing a blade as positioned for use as a knife.

Figure 2 is an end elevational view thereof.

Figure 3 is a perspective view of the removable blade holding end member.

Figure 4 is a longitudinal sectional view illustrating a modified form of the invention.

Figure 5 is a perspective view of the removable blade holding end member.

Referring to the drawing in detail, the container is indicated generally by the reference character 5 and is preferably formed of sheet metal so that it may be readily and easily constructed by a single operation of a stamping machine.

As shown, the casing is tubular in forma-

tion and the tapered ends thereof are provided with threads 6, the threads at one end of the container being designed to receive or cooperate with the threads 7 of the removable blade supporting member 8 to secure the blade supporting member in one end of the container 5.

This blade supporting member is also formed of sheet metal and has tapered extremities tapering from the central portion thereof, to the end that as the blade supporting member 8 is positioned in one end of the container, which also tapers slightly, a binding action will be set up between the blade holding member 8 and container, causing the blade holding member to firmly grip the blade, which is indicated at 9, and which has one of its ends positioned in the blade supporting member.

While the blade supporting member 8 is substantially tubular in formation, the same is split throughout its length, the ends thereof being extended inwardly defining flanges 10 which in practice engage the sides of the blade to hold it against movement. To further insure against movement of the blade when positioned in the blade holding member 8, a groove 11 is provided within which the back of the blade rests, as shown by Figure 1.

The reference character 12 designates a removable closure for closing one end of the container 5 and affords means whereby the blades contained within the member 5 and which have been discarded as razor blades, may be removed or replaced.

The cap 13 which is shown in Figure 1 as positioned over one end of the container, is primarily designed as a guard cap to be positioned over the blade 9 when the device is not in use, it being understood that the formation of the threads of the container is such as to permit the cap to be readily positioned.

As shown by Figure 4 of the drawing, the container which is indicated by the reference character 14 is also tubular in formation, one end thereof being closed as at 15, the opposite end being closed by the blade holder 16. Blade engaging flanges 17 form a part of the blade holder 16 and securely grip the

blade positioned therebetween, when the blade holder is forced into the open end of the container 14. The blade holder 16 also tapers towards its ends so that when forced into the open end of the container 14, the sides of the holder will be contracted to accomplish the purpose of the invention.

From the foregoing it will be obvious that the container provides not only a receptacle 10 to receive discarded razor blades, but affords 15 a convenient handle, should it be desired to position one of the blades in one end of the handle, to use the device as a knife, for cutting the finger nails, trimming pencils or 20 similar uses.

15 I claim:

A combined blade container and knife including a tubular body portion having a tapered open end, a holder embodying a tubular member split along its side, portions of 20 the blade holder adjacent to the split being extending inwardly defining wide blade engaging flanges, a blade positioned within the blade holder between the flanges, and said 25 flanges adapted to grip the blade when the blade holder is forced into the tapered end of the tubular body portion.

In testimony that I claim the foregoing as my own, I have hereto affixed my signature.

30 JOHN S. STRINGFELLOW.
